WITNESS:

INVENTOR
BY *Victor J. Evans*

ATTORNEY

UNITED STATES PATENT OFFICE

WARWICK B. CANNIFF, OF MARINE ON SAINT CROIX, MINNESOTA

CLOTHESPIN

Application filed June 29, 1929. Serial No. 374,724.

This invention relates to improvements in clothes pins and contemplates the provision of means included upon the upper portion thereof whereby the same may be hooked or 5 looped over a clothes line or the like in order that the clothes or garments suspended from the lower portion thereof will not be permitted to contact with the clothes line or wire in order to prevent the same from freezing thereto in cold weather, which are frequently torn when removing the same therefrom.

Another object of the invention is the provision of a novel form of clothes engaging 15 means including upon the lower end portion of the device which owing to its peculiar construction may readily and easily engage the garments or clothes to be hung or suspended from the clothes line and having 20 locking means included upon the upper portion thereof which will lock the clothes engaging means when the same are in position and ready for use.

With the above and other objects in view, 25 the invention further includes the following novel features and details of construction, to be hereinafter more fully described, illustrated in the accompanying drawing and pointed out in the appended claim.

30 In the drawings:

Figure 1 is a detail of the clothes pin attached to a clothes line and supporting a garment from the lower end portion thereof.

Figure 2 is a side elevation of the clothes pin per se.

Figure 3 is a front elevation thereof.

Referring to the drawing in detail, wherein like characters of reference denote corresponding parts, the reference character 10 indicates a clothes line or the like of which the present invention is supported, and forms no part of this application outside of being merely illustrated for purposes of illustration only.

45 In the present invention, and in order to provide the clothes pin as aforementioned I provide a singular length of wire which may be constructed of any suitable metal or the like but which is preferably galvanized or 50 rust proof in order that the same will not

rust when subjected to dew, rain or the like so that the rust caused by the same will not fall therefrom on to the clothes or the like suspended from the lower end portions thereof and the disagreeable rust stains appearing 55 upon clothing when used in other types of clothes pins will not occur. To this end I provide a singular length of wire which is bent upon itself adjacent the intermediate portion thereof as clearly illustrated as at 11 and which end portions extend in parallel 60 relation upwardly and outwardly offset as at 12 in order to provide a suitable opening or passage whereby the clothes line 10 or the like may be inserted therein in order to support the clothes pin. The opposite end portion of the ends extend outwardly, rearwardly and downwardly as at 13, one end portion thereof is substantially offset as at 14 and extends outwardly and inwardly and 65 in order to provide a loop 15 and has provided upon the lower end portion thereof a companion clothes pin member 16. The corresponding end portion being correspondingly bent or offset as at 16 and extends in 70 the same outward and inward curvature in order to provide a loop 17 and which has its opposite end portion imbedded in the upper portion of a companion clothes pin member 75 18. These companion clothes pin members 16 and 18 respectively include inner fitting 80 cut-out portions 19 and 20 respectively which are adapted to engage or receive clothing or the like as indicated at 21 in Figure 1 of the drawing. A locking or holding ring is provided upon the upper portions of the companion clothes pin members 16 and 18 respectively 85 and which is adapted to slide downwardly thereon when the clothes pins are in engagement with the clothes or the like 90 21 in order that the spring tension of the loops 15 and 17 respectively will be checked in order that the said clothes pin members 16 and 18 respectively will firmly engage the clothing 21 in order to prevent accidental 95 displacement of the clothing thereon.

In the use and operation of the present invention it would be clearly apparent that upon passing the intermediate bent portion 11 of the supporting means over and upon 100

the clothes line 10 that owing to the offset portion 12 thereof a suitable opening will be provided between the sides of the supporting means in order to freely receive said clothes line 10. When it is desirous of engaging clothing or vice versa the loop portions 15 and 17 are grasped in one hand and compressed in order to space or spread the companion clothes pin members 16 and 18 respectively and when compressing the same the thumb nail of the same hand may engage the ring 22 in order to push the same upwardly and free from engagement with the outer side walls of the companion clothes pin members 16 and 18 in order to allow the same to spread a maximum distance in order to receive clothing or the like of all thicknesses. After the clothes 21 or the like have been inserted between and engaging the cut-out portions 19 and 20 of the companion clothes pin members 16 and 18 the clothes pin members are then grasped or compressed against the clothing in order to force the same into the cut-out portions therein and upon sliding the ring 22 downwardly upon the upper end portions thereof the same will be locked in the position desired in order to support the clothing.

It is also to be noted that owing to the peculiar construction of the above mentioned invention that a pair of gloves or the like may be worn when hanging up or taking down clothing in order to prevent the hands from freezing or engaging of the cold wire composing the supporting means of the clothes pin owing to the fact that only a minimum amount of stress is required upon the looped portions 15 and 17 thereof in order to expand the companion clothes pin members 16 and 18 respectively. If it is desirous of taking down the clothing without removing the companion clothes pin members 16 and 18 from the clothing 21 the intermediate portion 11 may be lifted outwardly in order to become disengaged from the clothes line 10 whereby all of the clothes may be taken down with the clothes pins thereon.

The invention is susceptible of various changes in its form, proportions and minor details of construction, and the right is herein reserved to make such changes as properly fall within the scope of the appended claim.

Having thus described my invention what is claimed is:

55 A clothes pin of the character described comprising a single length of wire bent upon itself and looped over and about a clothes line, the ends of the wire extending inwardly and downwardly from the bent portion for 60 intersecting relation to provide oppositely converging bent portions therebeyond, the ends of the oppositely converging bent portions being also disposed in intersecting relation and terminate to provide parallel end 65 portions, clothes engaging pin members car-

ried upon the parallel end portions, and securing means slidably received upon the upper portions of the companion clothes engaging pin members.

In testimony whereof I affix my signature. 70
WARWICK B. CANNIFF.
